BUILT-UP CONTAINER

Filed Feb. 14, 1940

UNITED STATES PATENT OFFICE

2,221,426

BUILT-UP CONTAINER

Edward Leon Whittier, Elizabeth, N. J.

Application February 14, 1940, Serial No. 318,912

12 Claims. (Cl. 312—144)

This invention relates to wardrobes, cabinets and the like and particularly to those constructed from a collapsible folding unit comprising the four sides of the structure and two substantially similar top and bottom or end sections the latter being interlocked with the top and bottom edges of the side and rear walls and with the upper and lower rails of the front side door frame. This arrangement facilitates the novel assembly of the three main packaged-for-shipment parts and provides a novel compact package for shipment of the three parts. Heretofore such containers have been shipped in a package containing four separate main parts requiring the user to assemble four instead of three separate parts.

An object is to provide a device of this class consisting of a unit composing the walls made and assembled at the manufacturer's plant from two parts one of which is a four-hinge-point-foldable part of suitable preferably fibrous material providing the side and rear portions of the container and having its forward vertical side edges fastened in grooves formed in vertical stiles of the other of front door frame part. When so fastened the two parts forming the unit of four sides are arranged for shipment thereof in novel folded manner, the rear or back being folded against one side and the other side being simultaneously folded against the front and the four joined sides being then folded into parallelism.

Other objects are to provide means in said side portions facilitating said folds; to provide means in the top and bottom members facilitating removable attachment thereof with the sides; to provide cooperative means in the top, bottom and sides for uncoupling the said top, bottom and side units to provide a door frame unit having a peripheral groove of unitary structure receiving the front edges of the top, bottom and wall members to form a simple, neat finished appearance to the complete device.

Patent Number 2,009,482 to Derman discloses related matter but the advantages and other objects of the present invention thereover will be readily apparent and clearly understood from the accompanying drawing and following description forming part thereof.

In the drawing:

Fig. 1 is a perspective view of my device with parts of the structure broken away and in section.

Fig. 2 is a transverse section on line 2—2 of Fig. 1.

Fig. 3 is a transverse section on line 2—2 of

Fig. 1, showing the position of the parts upon being folded from their position of Fig. 2.

Fig. 4 is a similar view showing the position the parts assume upon being folded from the position of Fig. 3.

Fig. 5 is a vertical cross section on line 5—5 of Fig. 1.

Fig. 6 is a perspective view looking upward at the inside of the top.

Fig. 7 is a transverse section fragmentary view 10 of a portion of the door frame showing another method of fastening the free side edge to the frame.

Fig. 8 is a plan schematic sectional view showing my device when made with additional width 15 and having added section X.

Fig. 9 is a schematic view showing the device of Fig. 8 in folded position for shipment thereof.

The part 10, Figs. 1 and 2 as shown, is formed from a single sheet of preferably fibrous corrugated board and consists of three wall portions 10a and 10b, the sides, which are hingedly coupled at lines 13, 13a with 10c the back. Said sides have front end portions 10a', 10b' being hingedly coupled at lines 13a and 13b and are 25 suitably permanently fastened as with staples S in longitudinal grooves 19 in the front side members 10f of the door frame. In the packing-for-shipment of the device it is seen that a side such as 10a may be folded against the front 10f, and 30 the other side 10b simultaneously folded against the back 10c (see Fig. 3) and then further folded about crease lines 13a, 13b to the position of Fig. 4 so that the unit of four sides are in substantial parallelism to form a relatively flat package. 35 Other folds and methods may be used.

The top 11 and bottom 11a are of substantially similar construction although the top may have a transverse clothes-hanger-rod 14 which may be removably turnably fastened in hooks 141, the 40 rod having mounted in each end a flat head pin or screw or the like 142 to be cooperatively received by the hooks.

Each part 11, 11a consists of a panel 15 attached to a frame 16 consisting of rails 16a, 16b 45 and 16c, the rails being grooved on their inner surfaces as at 17 to enclosingly receive the top and bottom edges of the walls 10a, 10b, 10c (see Figs. 5 and 6) and said panel has a projecting tongue 15a (Fig. 5) which facilitates the attachment of 50 the parts 11, 11a to the front door frame 10f, the tongue removably entering grooves 18 to be enclosed therein. It is seen that the frame 10f has uniform peripheral groove 18, 19, Fig. 1, the upright portions of which have the ends of portions 55

$10a'$, $10b'$ permanently fastened therein and the horizontal ends thereof having portions $15a$ removably mounted therein.

In attaching members 11 , $11a$ with the four-walled unit member 10 , the portions $15a$ are first inserted in their respective grooves 18 and the wall top and bottom edges are then placed in their respective grooves 17 . I prefer to removably suitably tie the three units 10 , 11 and $11a$ together with cooperative means such as pliable wire 30 having a portion thereof permanently fastened to the top and bottom members and the free end thereof $30a$ then wound around a suitable hook means 31 (see Figs. 1, 5 and 6). This method permits break-down without scar of the units and provides removable independent connection of the ends with the sides and no tools or separate fastening means are needed or applied by the user in assembling the parts.

Other fastening means and methods may be used.

The unit 12 includes a door 20 which is hingedly supported on the frame $10f$ on hinges 21 and it may have latch means (not shown) at its free side edge. The inward movement of the door may be limited by flange stop $20a$ formed on its frame. The door 20 consists of a frame composed of side members $20a$ and top and bottom cross members $20b$, the inner edges of all of which are grooved as at 24 , Fig. 1, to receive a panel 25 which is inserted as the frame is being assembled. A corrugated nail N is preferably placed across the mitered edges of the frame to fasten it together.

It is seen that in packing the complete device of three units for shipment, the top and the bottom parts 11 and $11a$ may be conveniently placed upon the folded main-body-wall-with-frame part to provide a relatively thin flat elongated package which may be suitably wrapped. In my wide type of cabinets as schematically shown in Figs. 8 and 9 said top and bottom parts may be placed between the door frame and the folded members $10a$, X , $10c$, $10b$ so as to be enclosed therein when shipped.

In Fig. 7, is shown an embodiment of my invention in which the portions $10a'$, $10b'$ are permanently fastened as with staples S in longitudinal grooves 19 formed in the outside face of frame vertical end stile $10f$ the free edge of the side walls $10a$, $10b$ being unaligned with said sides both in built-up or broken down position. This method of attachment lends added decorative fibre board area to the side wall area and reduces the exposed area of the side stile $10f$.

It is to be noted that in making up my cabinets I prefer to first fix the upright side stiles $10f$ on the corrugated paper side free ends and then attach the top and bottom cross frame pieces to thus form the frame with the walls attached rather than to form the frame and then attach it to the sides.

Figs. 8 and 9 are plan schematic views (on reduced scale) of my method of folding the sides $10a$, $10b$, $10c$ in cabinets that are wider by the distance X than that shown in Figs. 1 to 6 there being an additional fold line $13d$ in the back wall. Said back wall having been obviously widened by the distance X this portion assumes the position shown in Fig. 9 when folded for shipment.

Parts may be used without others. The disclosure is intended to be illustrative rather than limitative.

I claim:

1. A container of the class described consisting of three removably connected main parts one of

which comprises a single sheet of material fixed on a front-door-frame-wall together hingedly forming a front framed opening panel wall connected with back and side integral walls, the sheet having side front edges and end edges, a fold line parallel to and adjacent each sidefront edge whereby the walls are connectedly foldable into substantially parallel sections, two end parts having front edges and means removably coupling the end edges of the side and back walls therewith, said front frame having a peripheral integral groove enclosedly receiving the front edges of the side walls and end parts therein and having a door hingedly mounted thereon, said front edges of the sides alone fixed in said frame groove.

2. The device of claim 1 including means removably holding the three main parts together when assembled for use as a built-up container.

3. The device of claim 1 including means removably holding the three main parts together when assembled for use as a built-up container comprising means holding the top and bottom each independently to the sides.

4. The device of claim 1 including means removably holding the three main parts together when assembled for use as a built-up container comprising means holding the top and bottom each independently to the sides comprising a tie piece on the top and on the bottom having an end, and hooks on the sides having the tie ends wound therearound.

5. A container of the class described consisting of three removably connected main parts one of which comprises a single sheet of material fixed on a front-door-frame-wall together hingedly forming a front framed opening panel wall connected with back and side integral walls, the sheet having side front edges and end edges, a fold line parallel to and adjacent each side front edge and a fold line in the back parallel to and adjacent one of the sides, whereby the walls are connectedly foldable into substantially parallel sections, two end parts having front edges and means removably coupling the end edges of the side and back walls therewith, said front frame having a peripheral integral groove enclosedly receiving the front edges of the side walls and end parts therein and having a door hingedly mounted thereon, said front edges of the sides alone fixed in said frame groove.

6. The device of claim 5 including means removably holding the three main parts together when assembled for use as a built-up container.

7. The device of claim 5 including means removably holding the three main parts together when assembled for use as a built-up container comprising means holding the top and bottom each independently to the sides.

8. The device of claim 5 including means removably holding the three main parts together when assembled for use as a built-up container comprising means holding the top and bottom each independently to the sides comprising a tie piece on the top and on the bottom having an end, and hooks on the sides having the tie ends wound therearound.

9. A container of the class described consisting of three removably connected main parts one of which comprises a single sheet of material fixed on a rectangular front-door-frame-wall together hingedly forming a front framed opening panel wall connected with back and side integral walls, the sheet having side front edges and end edges, a fold line parallel to and adjacent each side

front edge, and a fold line in the back parallel to and adjacent one of the sides, whereby the walls are connectedly foldable into substantially parallel sections, two end parts having front edges and means removably coupling the end edges of the side and back walls therewith, said front frame having a peripheral integral groove enclosedly receiving the front edges of the side walls and end parts therein and having a door hingedly mounted thereon, upright parts of said groove being formed in the outer side surface of the frame vertical sides, said front edges of the sides alone fixed in said frame vertical groove unaligned with and reinforcing said side walls and concealing part of said front frame.

10. The device of claim 9 including means re-

movably holding the three main parts together when assembled for use as a built-up container.

11. The device of claim 9 including means removably holding the three main parts together when assembled for use as a built-up container comprising means holding the top and bottom each independently to the sides. 5

12. The device of claim 9 including means removably holding the three main parts together when assembled for use as a built-up container 10 comprising means holding the top and bottom each independently to the sides comprising a tie piece on the top and on the bottom having an end, and hooks on the sides having the tie ends wound therearound. 15

EDWARD LEON WHITTIER.
